CLAIM

The ornamental design for a sterile, disposable, resealable breast-milk storage bag, as shown and described.

DESCRIPTION

FIG. 1 is a front elevation view of a sterile, disposable, resealable, breast-milk storage bag showing my new design; FIG. 2 is a rear elevation view of the bag shown in FIG. 1; FIG. 3 is a top-plan view of the bag shown in FIG. 1; FIG. 4 is a bottom-plan view of the bag shown in FIG. 1; and,

FIG. 5 is a side elevation view of the bag shown in FIG. 1, the left and right side views of the bag being identical.
